No. 813,901.

PATENTED FEB. 27, 1906.

P. G. LEMING, F. EIKLOR & C. W. GRANT.

MOLDING MACHINE.

APPLICATION FILED MAY 6, 1905.

UNITED STATES PATENT OFFICE.

PARMENOS GRANT LEMING, FRED EIKLOR, AND CHARLES WILLIAM GRANT, OF URBANA, ILLINOIS; SAID EIKLOR AND GRANT ASSIGNORS TO SAID LEMING.

MOLDING-MACHINE.

No. 813,901.

Specification of Letters Patent.

Patented Feb. 27, 1906.

Application filed May 6, 1905. Serial No. 259,113.

To all whom it may concern:

Be it known that we, PARMENOS GRANT LEMING, FRED EIKLOR, and CHARLES WILLIAM GRANT, citizens of the United States, 5 and residents of Urbana, in the county of Champaign and State of Illinois, have invented a new and Improved Molding - Machine, of which the following is a full, clear, and exact description.

10 Our invention relates to a machine for molding purposes, and is especially applicable for the manufacture of hollow cement building - blocks, although it is capable of general use for molding plastic materials.

15 Our invention comprises a hand-operated machine provided with an automatic core-extractor and means whereby the molded article can be readily transferred from molding position to a pallet and released from the 20 mold in a rapid and efficient manner.

Reference is to be had to the accompanying drawings, forming a part of this specification, in which similar characters of reference indicate corresponding parts in all the figures.

25 Figure 1 is a perspective view of a machine constructed in accordance with the principle of our invention. Fig. 2 is a longitudinal sectional view thereof on the line 2 2 of Fig. 3.

30 Fig. 3 is a sectional view on the line 3 3 of Fig. 2, and Fig. 4 is a perspective view of a portion of the end of a mold which may constitute a part of the machine.

The machine is provided with a frame 10, 35 provided with a support 11 for a tamping-sill 12. This tamping-sill in our preferred form is raised above the main part of the frame at a height substantially equal to the heights of the mold which is employed; but this is a detail that can be departed from. The main frame extends to the right for some distance and is provided with a pallet-sill 13. These two sills are located at opposite ends of the frame, and midway between them are placed 40 one or more supports 14 for a movable frame 15, which is preferably pivoted to these supports by means of a shaft or rod 16. The frame 15 is shown as comprising two bars extending from the rod 16 in the same direction 45 and provided with handles 17 at their ends

50 by means of which the device can be manipulated. The frame is provided with a mold-plate 18, which virtually constitutes the bottom plate of the mold. To this plate are secured spring-hinges 19, which are so constructed as to normally hold the several mold-walls 20 in open position, as indicated in dotted lines in Figs. 2 and 3. Upon two opposite walls 20 are pivoted locking-bars 21, having oppositely-disposed notches 22 for engagement with lugs 23 upon the other mold-walls.

55 It will be readily observed that when the locking-bars are moved into the position shown in Fig. 4 all of the mold-walls will spring outwardly into the position shown in dotted lines. These parts constitute the main portion of the mold; but it is preferably provided with other features, especially one or more cores 24. These cores are adapted 60 to project through an opening 25 in the mold-plate 18, so as to enter the mold in an obvious manner. They are made in any desired shape, but are preferably tapered to facilitate drawing through the mold-plate. These 65 cores are pivotally or otherwise movably connected with core-moving bars 26, which are pivoted upon the shaft 16 and are provided with extensions 27, adapted to engage the under side of the tamping-sill 12 when the 70 frame 15 is swung over into reverse position, as shown in Fig. 2. The projections 27 may conveniently be provided with steel plates 28 to prevent excessive wear. A pallet 29 is 75 preferably provided.

80 The operation of the device will now be described. The frame 15, carrying the cores 24 in the proper position in the mold, is first placed on the tamping-sill, and with the mold-walls fixed in a closed position the 85 molding material is placed in the mold and tamped. The pallet is then placed on top of the mold, if desired, and the operator by grasping the handles 17 turns the whole frame over upon its pivot and deposits the 90 molded block and pallet upon the pallet-sill 13, or in certain kinds of molding the pallet can be left upon the pallet-sill and the mold deposited on that directly. As the frame 95 15 approaches the position in which the mold 100

will come into contact with the pallet or the pallet with the pallet-sill the plates 28 strike the lower surface of the tamping-sill, and consequently arrest the motion of the cores 5 with respect to the mold. The continued motion of the mold and frame 15 therefore draws the cores from the molded article. If the arms 21 are now moved into the position shown in Fig. 4, the mold-walls will spring 10 out from the molded article, and even if provided with roughened or figured mold-surfaces they will leave the article and thereby free it from the mold. The frame 15 is now turned back to position on the tamping-sill 15 and the molded article is left in the position shown in Fig. 1.

A machine constructed in accordance with the principle of this invention is exceedingly simple and can be manipulated by a single 20 operator with great efficiency and rapidity. The blocks or other objects molded are left in the exact state in which the mold is designed to leave them without any marring of the surfaces, and the delivery of the product 25 from the mold is rendered absolutely certain and very rapid. The mold is also restored to position for another operation with a minimum of trouble and a very small expenditure of energy.

30 Having thus described our invention, we claim as new and desire to secure by Letters Patent—

1. A block-molding machine having a pivoted frame, a mold thereon at a distance from 35 the pivot of the frame, and two sills located at a distance from the pivot of the frame equivalent to the distance between the pivot and mold.

2. A block-molding machine having a pivoted frame, a mold thereon at a distance from 40 the pivot of the frame, and two sills located at a distance from the pivot of the frame equivalent to the distance between the pivot and mold and on opposite sides of the pivot, 45 whereby the frame is capable of carrying the mold from one sill to the other.

3. In a molding-machine, the combination of two sills, a frame pivoted at a point midway between them, a mold on the frame, a 50 core, and means for automatically drawing the core from the mold when the frame is swung about its pivot.

4. In a molding-machine, the combination of two sills, a frame pivoted at a point midway between them, a mold on the frame, a 55 core, and means for automatically drawing the core from the mold when the frame is swung about its pivot toward one sill; said means being constructed and adapted to operate before the mold reaches that sill.

5. In a molding-machine, the combination

of two sills, a frame pivoted at a point midway between them, a mold on the frame, a core, and means for automatically drawing the core from the mold when the frame is 65 swung about its pivot; said mold having separable walls, and spring-hinges by which the walls are connected to the main part of the mold.

6. In a molding-machine, the combination 70 of two sills, a frame pivoted at a point midway between them, a mold on the frame, a core, and means for automatically drawing the core from the mold when the frame is swung about its pivot; said mold having separable walls, spring-hinges by which the walls are connected with the main part of the mold, 75 and means for locking all of the walls in closed position.

7. In a molding-machine, the combination 80 of a frame, a pallet-sill thereon, a tamping-sill, said sills being located at opposite ends of the frame and the tamping-sill being at a higher elevation than the pallet-sill, and a movable frame pivoted to the main frame at 85 a point midway between said sills.

8. In a molding-machine, the combination of a frame, a pallet-sill thereon, a tamping-sill, said sills being located at opposite ends of the frame and the tamping-sill being at a 90 higher elevation than the pallet-sill, a movable frame pivoted to the main frame at a point midway between said sills, and a mold located on said movable frame, the height of said mold being substantially equal to the 95 distance in elevation of the two sills.

9. A molding-machine, comprising a pivoted frame, a mold thereon, a core, a bar connected with the core and pivotally mounted with respect to the frame, said bar having 100 a projection, and means for engaging the projection to arrest the motion of the core while the frame is moving about its pivot.

10. A molding-machine, comprising a movable frame, a mold thereon, a core, a bar 105 connected with the core, said bar having a projection, and means for engaging the projection to arrest the motion of the core while the frame is in motion.

11. In a molding-machine, the combination 110 of a frame, a pallet-sill thereon, a tamping-sill, said sills being located at opposite ends of the frame and the tamping-sill being at a higher elevation than the pallet-sill, a frame movably mounted on the main frame, 115 and a mold located on the last-named frame.

12. In a molding-machine, the combination 120 of two sills, a frame movably mounted between them, a mold on the frame, a core, and means for automatically drawing the core from the mold when the frame is moved from one sill to the other.

13. In a molding-machine, the combination of a sill, a frame movably mounted adjacent thereto, a mold on the frame, a core, and means for automatically drawing the core from the mold when the frame is moved toward said sill, said means being constructed and adapted to operate before the mold reaches the sill.

In testimony whereof we have signed our

names to this specification in the presence of 10 two subscribing witnesses.
